ARTHUR O. AUSTIN, OF NEAR BARBERTON, OHIO

PROCESS AND APPARATUS FOR TREATING CONDUCTORS

Application filed August 30, 1930. Serial No. 479,010.

This invention relates to a process for restricting corona losses from high voltage conductor lines and to apparatus for treating the line.

5 The invention has for one of its objects the provision of a process and apparatus which will render a conductor line less liable to corona losses, and by which the line may be quickly and economically treated although 10 it may be located in a position where it is not easily accessible.

Other objects and advantages will appear from the following description.

The invention is exemplified by the combination and arrangement of parts shown in 15 the accompanying drawing and described in the following specification and by the process explained in the specification. The invention is more particularly pointed out in the appended claims.

In the drawing:

Fig. 1 is an elevation of one form of apparatus for treating a conductor line according to the present invention.

25 Fig. 2 is a section on line 2—2 of Fig. 1.

Fig. 3 is a section on line 3—3 of Fig. 1.

In the transmission of power at high voltages, it is essential that the corona losses be maintained within economical limits. Any 30 expedient which will permit of a higher operating voltage without producing prohibitive corona losses or excessive radio interference, due to discharges from the conductor, is of considerable economical importance in 35 many transmission lines.

In transmission lines where the amount of energy transmitted is not sufficient to warrant a large diameter of conductor but where it is desirable to use a high voltage because 40 of interconnection with other lines or to provide for future loads which would require a high voltage, it may be very desirable to use a small conductor. With the present invention, it is possible to use a small conductor 45 and avoid some of the difficulties which have heretofore been encountered in transmission work. On some systems, it is advisable to raise the corona point or to reduce radio interference in restricted localities only, in 50 which case the improved method of treating

the conductor may be warranted even though not applied to a transmission line as a whole.

In my prior Patent #1,626,777 an improved type of conductor is shown for reducing discharge from high voltage conductors. With this type of conductor, it has sometimes been difficult to obtain an insulating coating which will have the desired length of life, although an improvement in the coating may at any time greatly improve this construction. In order to take advantage of the insulated strand of the conductor covered with a dielectric medium, shown in my prior patent, a method of coating the guard or control strands is provided by the present invention which is easily and cheaply applied. By using this method with conductors having guard strands, it is possible to apply an insulating covering very easily by a traveling mechanism placed on the conductor. As the guard strands constitute but a small portion of the surface, it is possible to coat these without applying a large amount of material which might otherwise be required, due to the capillary attraction of the strands.

The method, however, is applicable for improving the ordinary rope lay or smooth lay conductors used in transmission lines where it is desirable to reduce the discharge from the conductors. The method applies more particularly, however, to the special type of conductors having projecting guard strands as disclosed in my prior patent.

One method of treating the conductor according to the present invention involves the use of a small paint or enamelling carriage which may be drawn along the conductor by any suitable means. The nature of the equipment used for applying the coating will, of necessity, depend upon the style of conductor. The coating may be applied by flowing the material over the conductor with a suitable wiping means to take off excess material or by a suitable air brush or a roller carrying the coating material which is taken from a suitable supply. If desired, the paint or enamelling carriage may be operated by hand with an operator seated with the mechanism; the carriage being so arranged that

he may operate the coating equipment and propel the carriage along the conductor.

In the case of lines where it is known that enamelling or dielectric coating will be applied from time to time, it is desirable that the clamps or attachments at the towers used for supporting the conductor be so formed that the coating equipment may pass over these obstructions readily. This is readily

carried out by providing proper ribs or grooves for the wheels which support the carriage. Many enamels or dielectric coatings are greatly improved by the application of heat during the curing or drying process.

This heat may be readily supplied in a transmission line by using sufficient current in the conductor for curing purposes. By coating the conductor with enamel of increased dielectric strength, it is possible to reduce the

losses due to roughness on the conductor either produced in drawing or by deposits or by damage during installation.

It is readily seen that where conductors are used with the extending control or guard

strands, the amount of coating material required may be very small as compared to the coating of an ordinary conductor. The weight of the conductor will also be less than the regular conductor coated as in the latter case an appreciable amount of material is likely to be drawn into the conductor through capillary attraction. It is possible, however, to use a very thick enamel for coating which may be applied by a series of flexible rollers.

While these rollers are spaced some distance apart, it is possible that several light coatings may be applied in rapid succession without using a large quantity of material, which is of little use.

Where tower clearances are sufficient, it is possible to arrange a carriage so that an operator may coat the conductor without interruption of service. If the means used to propel or draw the coating carriage is insulated from ground, it is also possible to treat the conductors during the normal operation of the transmission system. The means adopted for coating will, of necessity, depend upon the conditions and the result desired.

Where the current flowing in the conductor is of appreciable magnitude, it is possible to use the magnetic field set up by the current in the conductor to operate a motor which will propel the carriage and operate the painting mechanism or compressors. This is probably the preferred method of coating a power conductor and, if desired, an operator may attend the carriage so operated.

In the form of apparatus shown in Fig. 1, the conductor 10 is used to transmit an alternating current. In order to take power from this alternating current, a magnetic core 11 with a secondary winding 12 is placed around the conductor. This magnetic core may have a closed magnetic circuit or if

made amply large may have an air gap. In general, the magnetic circuit will have a removable block or gap piece 13 shown in Fig. 2; the removable gap piece being used to allow the core to be slipped over the conductor and also to control the flux flowing in the magnetic core 11 which, in turn, will control the current or voltage in the secondary 12. It is evident that by adjusting the air gap the amount of flux flowing in the core may be adjusted for variations of current in the conductor 10. It is not necessary, however, that this adjustment be made providing the apparatus to be operated will work over the range of current induced in the secondary or where this is controlled by an impedance in the secondary circuit or by taps on the same.

The current from the secondary circuit is run to a motor 14 which in turn is used to operate tractor wheels 15 to propel the carriage and also to operate coating rollers or brushes 16 which dip into a suitable coating tank 17.

It is readily seen that if the line is not in normal operation it may be short-circuited or grounded at any desirable place and sufficient current sent through it to operate the coating mechanism. Under this condition, the voltage on the line may be very small, particularly if the point of short-circuit is in the vicinity of the place where the work is being carried on. By short-circuiting the conductors in advance of the place where coating is being carried on, it is possible to have a high voltage on the line at the source of power in order to force the necessary current across the line, but at the same time the voltage will be negligible in the vicinity of the coating operations.

A short may be placed between conductors in advance of the operation or from a conductor to ground which will reduce the potential at this point. It, of course, is possible for the operating motor to operate an air compressor, if the conductor is coated by means of ordinary spray guns or by apparatus specially designed for the work. Excess material may be readily removed from the conductor by brushes or an air blast operated by the motor. It is evident that with this type of mechanism it is possible to coat conductors in very inaccessible places and to supply the necessary power.

In the stringing of conductors on their supports, the surface of the conductor is frequently damaged by drawing it over rocks or the tower members. With the above described equipment, it is very easy to smooth up the conductors by substituting the proper smoothing or polishing equipment for the coating brushes or rollers. It is also possible to remove dirt and small pieces of metal from the conductor. Many small pieces of metal are produced during the drawing operation

which adhere to the conductor surface and promote discharge from the surface; hence, the removal of these will improve the condition of the conductor which might otherwise require a considerable length of time before the adhering particles would be removed by the action of the weather and other causes.

As a uniform roughness on the surface of a conductor tends to eliminate discharge points and, at the same time, provides a much better surface for the holding of the enamel or insulating covering, it may be advisable in some cases not only to clean the conductor so that the enamel will hold but also to further prepare the surface by means of a small scratch brush or sandblast. This can be readily taken care of by a carriage in advance of the one applying coating or can be driven by the same equipment providing there is enough energy. Unless a conductor has been weathered for some time, it is generally advisable to clean the surface in advance of applying the coating as oil or tallow used in the drawing of the conductor may interfere with the adherence of the coating. Much of the oil or grease and small chips which will tend to cause a discharge may be washed off by a suitable brush equipment which is substituted for the coating rollers; a washing fluid being substituted for the coating material. In general, however, it is advisable to do the washing far enough in advance of the coating so that it will not interfere with the proper application of the coating. In some conductors, however, the capillary attraction may be used to hold the wash water on the interior of the conductor. This will tend to prevent the insulating compound from being fed into the center of the conductor.

40 I claim:

1. The process of treating a conductor while in operative position in a transmission line comprising the steps of supporting treating apparatus on the conductor propelling the apparatus along the conductor by power derived from the current in the conductor, and operating said device independently of its movement along the conductor by power also derived from current flowing in the conductor.

2. The process of treating a conductor having an alternating current flowing therein comprising the steps of moving a current transformer along the conductor while in position to be energized thereby and utilizing the current from the secondary of said transformer for operating apparatus independently of its movement along the conductor to treat the conductor.

60 3. Apparatus for treating a conductor while suspended in a transmission line comprising a carriage adapted to be supported on a conductor and to travel along said conductor, and a current transformer mounted on said carriage and having a removable core

section to permit insertion and removal of the conductor to and from said core section.

4. Apparatus for treating a conductor while suspended in a transmission line comprising a carriage adapted to be supported on the conductor and to travel on said conductor, a current transformer having a core mounted on said carriage in position to be energized by current flowing in said conductor, said current transformer having a secondary winding, a motor mounted on said carriage, and treating apparatus for said conductor operated by said motor.

5. Apparatus for coating a transmission line conductor while suspended in position in the line comprising a carriage arranged to be supported on the conductor and to traverse the conductor, a current transformer core mounted on said carriage and having a removable section to permit insertion of the conductor in said core, said current transformer having a secondary winding, and a motor mounted on said carriage and energized by current from the secondary winding of said transformer, a traction wheel propelled by said motor for moving the carriage along the line, and treating apparatus mounted on said carriage and operated by said motor.

6. Apparatus for coating a conductor while in position in a transmission line comprising a pair of wheels adapted to travel on the conductor, a frame suspended from said wheels below said conductor, a transformer core mounted on said frame and having an opening therethrough for receiving said conductor, a portion of said core being movable to permit insertion of the conductor therein, a secondary winding on said transformer core, a motor mounted on said frame below said conductor and connected with said secondary winding to be driven by current induced in said secondary winding by current in said conductor, a driving connection between said motor and one of said wheels for propelling said frame along said conductor, and apparatus mounted on said frame for applying a coating to the outer surface of said conductor, said apparatus being driven by said motor.

In testimony whereof I have signed my name to this specification this 29th day of Aug. A. D. 1930.

ARTHUR O. AUSTIN.
